RAILWAY SIGNALING SYSTEM.

1,097,197.

Specification of Letters Patent. Patented May 19, 1914.

Application filed September 10, 1903. Serial No. 172,568.

To all whom it may concern:

Be it known that we, JOSEPH C. THULLEN and LOUIS H. THULLEN, citizens of the United States, residing at Leetonia, county of Columbiana, and State of Ohio, and at Edgewood Park, county of Allegheny, and State of Pennsylvania, respectively, have invented or discovered new and useful Improvements in Railway Signaling Systems, of which the following is a specification.

Our invention relates to systems of railway signaling wherein the signals are operable by alternating currents of more than one phase and wherein both rails are utilized as a return for the propulsion currents of the car motors. Heretofore it has not been found feasible to utilize the sectional rail as a return for the direct current while using the rail to carry the alternating currents by which alone the signals may be operated.

We do not limit ourselves to any number of currents of different phase relation, or to any particular angle of phase relation that they may bear to each other, the number of phases and the angular relation thereof being varied to best accomplish the purpose in view of the condition to be met.

On the drawings, Figure 1 shows diagrammatically one form which our invention may assume. Fig. 2 shows diagrammatically a system similar to that shown by Fig. 1, except there are two relays for a section. Fig. 3 shows diagrammatically a system employing relays operable only by the combined action of two alternating currents of different phases. Fig. 4 shows diagrammatically a system employing an alternator generating currents of two phases, the relays being connected to the rails and the transformers. Fig. 5 is a view similar to Fig. 4, except the relays are connected to the mains instead of the transformers.

1 represents an alternator or source of alternating current, and 2, 2 are the mains across which the alternator is bridged. Across said mains is bridged the primary coil 3 of the stationary transformer 4 having the core 5. The said coil is connected across the mains by the leads 6.

7 is the common rail of an electric railway track and forms a continuous electric

conductor for the return of the car propulsion current, and 8, 9, 10 and 11 form the other rails of said track and are insulated from each other and the rail 7, except as hereinafter stated. The rails 8 to 11 divide the track into block sections 12, 13, 14, and 15, the ends of adjacent sections being indicated by 16 and 17.

The secondary coil 18 is wound over the primary coil 3 and has one end connected to the end 17 of the rail 9 by the lead 19 and the other end to the common rail 7 by 65 the lead 20, containing the resistance 21. The transformer 4 has also a second secondary coil 22 wound preferably on the side of the core 5 opposite the secondary 18. One end of the secondary 22 is attached at 70 23 to the lead 20 between the resistance 21 and the secondary 18, the other end being connected by lead 24 to the end 16 of the rail 8.

25 represents a pair of wheels and an axle 75 of a trolley car and may be considered as a diagrammatic representation of such a car.

26 is the trolley connected by wire 27 to the car and contacting with the trolley wire 28, to which current for propelling the car 80 is supplied by the dynamo 29 in circuit with the trolley wire and the rail 7 and one of the sections of the sectional rail.

Bridged across the rail 7 and the rail 9 is a relay 30 of any approved type, that 85 shown being a diagrammatic representative of a motor relay, whereof 31 is the armature composed of aluminum or copper, and 32, the circuit closer or switch secured to the armature. The relay is connected to the 90 rails 7 and 9 by the leads 33.

34 is a signal, shown diagrammatically as a semaphore, though it may be of any other type. The signal has two leads 35, whose circuit is closed by said switch 32. The relay 30 is not operable by the direct current returning by the rails.

The adjacent ends of block sections 13 and 14 are provided with a transformer and electric connections precisely the same 100 as those shown at the adjacent ends of block sections 12 and 13, except the core is open at one side and has an internal central projection 36 extending toward the open side thereof. We have placed on the last named 105 transformer and its connections the same

reference characters as on the first named ones, but with prime ('') marks. The adjacent ends of block sections 14 and 15 are provided with a transformer and connections the same as the other two, except the core is closed and has two internal projections 36' extending toward each other and the reference characters which appear thereon are the same as those on the first one named above but with second (") marks.

The windings of the main and auxiliary secondary coils 18 and 22 are, as described, shown to be such that the return propulsion passes through the lead 19, both secondaries, and the lead 24. The main secondary 18, when the primary coil 3 is energized, is acted on by more lines of force than the other secondary, as a larger number of the lines of force close their circuits without passing through the coil 22. The current therefore generated in the winding 18 is out of phase with that generated in winding 22. The same is true of the windings having the same numerals with prime and second marks. The current generated by the winding 18 traverses the lead 20, the common rail 7, the lead 33, the relay 30, the lead 33, the rail 9, and the lead 19 back to the winding 18. The current generated by the winding 22' traverses the lead 20', the common rail 7, the lead 33, the relay 30, the rail 9, and the lead 24' back to the winding 22'. The relay 30 is of such a character that it will be actuated to cause the switch to close the local signal circuit 35 when the alternating currents of different phases from the windings 18 and 22' act conjointly, or also by currents from each winding separately.

The resistance 21 can be either inductive or non-inductive, as the case may require, or can be omitted, if the conditions demand it. The object of the resistance, if non-inductive, is to limit the current flowing through the secondary windings 18 and 22, either direct or alternating, or from the secondary windings themselves or from either the rails conveying the return propulsion current from the cars or from any other source.

Transformers 4' and 4'' by reason of the projections 36 and 36' furnish paths for the return of magnetic lines of force, which will divert more of said lines from the secondary 22' and more lines will be diverted from the secondary 22'' than from the secondary 22'. Hence the phases of the currents produced by the secondaries will not only differ in each transformer, but the currents in each transformer will differ in phase from each other. Of course, all the transformers may be alike, if preferred.

The cores can be composed partly of good, and partly of poor, magnetic substances, as wood, brass, zinc, or the like, inserted in the out gap between the sides of the core or

the projections therein. We do not limit ourselves to a core of any particular shape or material.

The transformers do not show all the kinds of transformers which will produce alternating currents of different phases; in fact, the alternating currents may be produced in different ways, as by the insertion of a non-inductive resistance in one circuit and an inductive resistance in another, or otherwise. The secondaries also furnish a path of low resistance for the return of the car propulsion current in addition to that furnished by the common rail, by utilizing the insulated rails 8 to 11 of the block sections. This has not been done heretofore to our knowledge.

The purpose of utilizing both rails of the track is to make a return of much lower resistance than if only the continuous rail were used. The path of the return current through the secondaries of the transformers is materially of greater resistance, as the turns of the coils are few; their cross-section large, and their material preferably copper. The wire of the coil might possibly be one and a half inches in diameter and the number of turns from one to three. However these dimensions and arrangements are to be varied from to meet the conditions which have generally to be determined specially for each case.

The operation is as follows:—No trains being on a block section, the alternator 1 will through the transformers cause the relay to close the local circuit of the signal for that section, showing that the track is clear. When a train enters a block the wheels and axles short circuit or shunt the relay for that block, causing it to open the local circuit of the signal, which thereupon displays a danger indication. As soon as the train passes off the block the signal again shows a clear track. This it will do even if one of the leads connected to the ends 16 and 17 be broken, as the relay is such as to operate as well with each alternating current as with both.

Referring now to Fig. 2, the reference numerals are the same as on Fig. 1, where the elements are the same, the additional relay having the same numerals as in Fig. 1, but with the exponents 2. In Fig. 2 the parts are the same except that a second relay 30² is bridged across the rails at the end of the block opposite that where the relay 30 is. More than two relays can be so bridged if desired. The purpose of a plurality of relays is that, if the bond wires or the rails of the track should break, still the signal would be shunted by a train. When no train is on the track, the switches of both relays close the semaphore circuit, and if either is shunted, the danger signal is displayed, as is evident.

The reference numerals on Fig. 3 are as on Fig. 2 so far as the elements are the same. Fig. 3 is like Fig. 2, except the relays and their connections. In Fig. 3, the 5 relay 37 is shown also of the motor type and can be actuated only by the combined action of two alternating currents of different phases. It receives one phase from the rails 7 and 9, as in Figs. 1 and 2, and the other 10 phase from the secondary 22 by means of the leads 36 bridged across the leads of the winding 22. The operation is the same as in Figs. 1 and 2. When a car enters a block it short circuits one of the currents necessary 15 to actuate the relay and permits the switch 32 to open the signal circuit.

The arrangement just described is not limited to obtaining an alternating current from such transformers as shown, but the currents of different phases may be obtained 20 from some other source, such as a direct lead from a dynamo, as shown in Fig. 5, or any apparatus giving a phase different from that supplied through the block rails by the 25 transformer at the end of the block.

In Fig. 3 the relay is not operated by means of alternating current traversing the block section and supplied thereto by the winding 18, but is only operated by the alternating current furnished by the transformer at the other end of the block section and another current having such an angle of phase difference that the currents will together operate the relay in the desired direction.

In Fig. 4, the reference numerals are the same as in Fig. 3, so far as the same are applicable. In Fig. 4 the alternator 1' generates alternating currents of two phases 40 which are led to the three mains 2'. The relays are connected to the remaining parts of the system as in Fig. 3, but the leads of the primaries 3 and 3" each have one limb connected to the middle main and the other 45 limb connected to one of the other mains, the last named limb of each primary being connected to different wires of the mains, so that the primaries receive current of different phases.

50 In Fig. 5 the reference numerals are the same as in Fig. 4 so far as the same are applicable. In Fig. 5, 1' is an alternating current generator furnishing an alternating current of two phases to the three mains 2'. The leads furnishing the relays with current of one phase are bridged across the rails as in Fig. 3, but the leads 38 which furnish the relays the other current of a different phase are bridged across the middle or common wire of the mains and one of the other wires. The relays are shown connected to one phase of the alternator or other source of alternating E. M. F. and the transformer to the other. The relay 37 is only actuated 55 by means of the combined action of the cur-

rent from winding 18 of the transformer 4 and the current from the winding 22" of the transformer 4" combined to form a resultant current of one phase for the relay, and the current from the alternator or source of 70 alternating current supply connected to the leads 38 has such a phase angle to the resultant of the two said windings as to make the relay operative. Also the phase of the lower leads 2' have such an angular relation 75 to the phase from the winding 22", exclusive of the phase from the winding 18 as to actuate the relay, but it is at such an angle as to be inoperative by the combined action of current from the lower leads 2' and the 80 winding 18. The alternator is merely illustrative of a source of any kind other than the transformers for supplying the relays.

We do not limit ourselves to any particular angle that the two alternating currents 85 may have to each other, but to such a phase angle as will operate the relays to the best advantage. In Fig. 5 the primaries are shown connected to the same pair of mains.

The advantages of using both rails as a return path for the propulsion car current may be secured even when the signals are all operable by alternating currents of the same phase.

Having described our invention, we 95 claim:

1. In combination, an electric railway the track rails of which are included in the circuit for the propulsion current, track sections comprising insulated rail sections, connections between adjacent rail sections for conducting the propulsion current from track section to track section, means comprised in said connections for supplying alternating signaling currents to the rails 100 of the track sections, and signals for the track sections controlled by said alternating currents in the track rails.

2. In combination, an electric railway the trackway of which is included in the circuit 110 of the propulsion current, a plurality of block sections including insulated rail sections corresponding to the block sections, a signal for each section, connections between adjacent rail sections, means in said connections for supplying alternating signaling currents to the track rails of the sections for the control of the signals, said connections and the rails of the insulated rail sections furnishing a path for the propulsion current.

3. In an electric railway signaling system, a continuous rail and a series of insulated rail sections forming the track rails for a car, a signal for each section, connections between the insulated rail sections, and means in 125 said connections for supplying alternating signaling current to the rails of the sections for the control of the signals, said continuous rail and said rail sections and the said 130

- connection constituting paths for the return of the car propulsion currents.
4. In an electric railway signaling system, a plurality of block sections, including insulated rail sections corresponding to the block sections, a signal for each section operable by alternating currents of different phases, a means including transformers for supplying each section with a plurality of currents having a difference in phase and capable of controlling said signal, the secondaries of said transformers furnishing a return for the propulsion current of the cars.
5. In an electric railway signaling system, a plurality of block sections comprising insulated rail sections corresponding to the block sections, a signal for each section, a transformer for each section having a plurality of secondary windings, a source of current to supply the transformers, the secondary windings of the transformers being connected and wound so as to act with the insulated rail sections as a return for the car propulsion current.
6. A system of automatic signaling for electric railways, comprising a generator, a power circuit including the rails of the trackway as a return, a plurality of transformers, a trackway divided into a series of sections by dividing one rail and introducing between its ends a conductor which forms a winding of one of said transformers.
7. A system of automatic signaling for electric railways, comprising a generator, a power circuit including both rails of the trackway, a trackway having one continuous rail and one sectional rail, a transformer located at each division of the sectional rail and having a winding connected across the divisions of the sectional rail, means for creating a difference in potential in each section of the trackway, and a signaling device in each section normally excited by such difference of potential but adapted to be short circuited when a car moves onto a section.
8. In combination, a railway track one of the lines of rails of which is electrically continuous and the other of which is divided by insulation to form track sections, a source of propulsion current, a source of alternating signaling current, a transformer adjacent an insulated point and comprising a primary winding connected with the source of signaling current and two secondary windings one of which is connected across the opposite lines of rails of one adjacent track section and the other of which is connected across the opposite lines of rails of the other adjacent track section, the two secondary windings being wound in opposite directions and having their connections to the continuous line of rails electrically connected so that the secondary windings serve to conduct propulsion current from either of the adjacent insulated rails to the other without substantially magnetizing the transformer core.
9. In combination, a railway track one of the lines of rails of which is electrically continuous and the other of which is divided by insulation to form track sections, a source of propulsion current, a source of alternating signaling current, a transformer adjacent an insulation point and comprising a primary winding connected with the source of signaling current and two secondary windings connected respectively across the opposite lines of rails of the two adjacent track sections, the two secondary windings being oppositely wound and connected in series between the insulated rails of the two adjacent sections so as to conduct the propulsion current between the two said insulated rails without substantially magnetizing the transformer core.
10. In combination, a railway track one of the lines of rails of which is electrically continuous and the other of which is divided by insulation to form track sections, a source of propulsion current, a source of alternating signaling current, a transformer adjacent an insulated point and comprising a primary winding connected with the source of signaling current and two secondary windings one of which is connected across the opposite lines of rails of one adjacent track section and the other of which is connected across the opposite lines of rails of the other adjacent track section, the two secondary windings of each transformer being so connected with respect to each other that the magnetic effect of the propulsion current flowing through the secondary windings from one adjacent insulated rail to the other will be substantially neutralized.
11. In combination, a railway track one of the lines of rails of which is electrically continuous and the other of which is divided by insulation to form track sections, a source of propulsion current, a source of alternating signaling current, a transformer adjacent an insulated point and comprising a primary winding connected with the source of signaling current and two secondary windings one of which is connected across the opposite lines of rails of one adjacent track section and the other of which is connected across the opposite lines of rails of the other adjacent track section, the two secondary windings of each transformer being so connected with respect to each other that the magnetic effect of the propulsion current flowing through the secondary windings from one adjacent insulated rail to the other will be substantially neutralized, track relays connected with the track rails and responsive to the signaling current impressed on said rails by the transformer secondaries,

and signals for the track sections controlled by said relays.

12. In combination, a railway track one of the lines of rails of which is electrically continuous and the other of which is divided to form block sections, a source of propulsion current connected with said rails, a transformer adjacent each junction of two sections, each transformer having two secondary windings one of which windings is connected across the rails of one adjacent section and the other of which windings is connected across the rails of the other adjacent section, the two secondaries of each transformer being so connected with respect to each other that the magnetic effect of the propulsion current flowing through said secondaries from one divided rail to the other is neutralized.
- 10 13. In combination, a railway, means for dividing the trackway thereof into block sec-

tions, means for supplying to the rails of each section a plurality of alternating signaling currents differing in phase, a relay for each section comprising two windings 25 one of which is connected with the rails of the section and the other of which is supplied with alternating current from a source other than said rails, said relay being responsive only to the combined influence of 30 the said signaling currents in the rails and the signaling current from the said other source, and signals for the block sections controlled by said relays.
